UNITED STATES PATENT OFFICE

CHARLES W. CURLE, OF SAN FRANCISCO, CALIFORNIA

LOW SLUGGING CUTTER MECHANISM

Application filed May 26, 1930. Serial No. 455,665.

This invention relates to improvements in low slugging devices, and has particular reference to a device for low slugging or cutting the end of a linotype slug.

5 The principal object of this invention is to provide an automatic means whereby the cutting action will only take place on that portion of the slug which does not bear any imprinting surface.

10 A further object is to provide a device which is simple in construction and therefore economical to manufacture.

A still further object is to produce a device which will be positive in its action, and will 15 not therefore ruin any slugs after passing therethrough.

Other objects and advantages will be apparent during the course of the following description.

20 In the accompanying drawing forming a part of this specification, and in which like numerals designate like parts throughout the same,

Figure I is a side elevation of my device.

25 Figure II is an end elevation showing the support broken away.

Figure III is a reduced top plan view.

Slugs which are cast in such casting machines as are commonly termed linotype machines or intertype machines all have a blank space at each end of the slug, which blank space is slightly below the surface of the face of the type cast upon the slug. This surface is so close to the type face that it even 30 causes what is known as an off-set, which is really a smear from the paper coming down into contact with the plain end of the slug.

It is therefore desirable to cut away the metal of the slug at the ends thereof, and this 40 operation is termed low slugging. It has heretofore been accomplished in various ways, tedious and uncertain, as with a knife or a pair of snippers; but, as far as applicant is aware, there have been no automatic means 45 employed for accomplishing this purpose.

Applicant has therefore devised a machine which consists of a support 5, having a table portion 6 upon which guides 7 and 8 are positioned. The support 5 has a movable bearing 9 supported thereunder through the me-

dium of a dove-tailed slide 11. This slide carries a lug 12, which bears upon a spring 13 mounted within the support.

A plate 14 is secured to the top of the support and has an arm 16 extending therefrom. This arm is in alignment with the nose 17 of a pivoted latch 18, pivoted as at 19 to bosses 21 formed upon the side of the bearing 9. A spring 22 serves to hold this nose 17 in engagement with the arm 16 for the purpose of which will be hereafter seen. An adjusting screw 23 is carried in the latch, which adjusting screw serves to adjust the same.

The lower end of the latch is provided with a contacting horn 24, which is in alignment with the path of the slug as the same passes between the guides 7 and 8. The bearing 9 has a spindle 26, upon which a pulley 27 is secured, and carries at its lower end a cutter head 28, which carries a plurality of cutters 29.

A rocker arm 31 is actuated in any convenient manner and has secured thereto a push-rod 32, which passes through the plate 14 and contacts the lug 12.

The result of this construction is that when the machine is started, the rocker-arm 31 actuates in such a manner that the push-rod 32 depresses the lug 12 and bearing 9 to the full line positions of Figures I and II. This permits the nose 17 of the latch 18 to move beneath the arm 16, due to the action of the spring 22. The amount of this movement beneath the arm is regulated by the screw 23.

We will now assume that the spindle 26 is 55 being rotated through a belt passing around the pulley 27. Therefore, if a slug A is passed between the guides 7 and 8, it will be engaged by the cutters 29 during its initial movement and shortly thereafter the end of 60 the horn 24 will engage the advancing type portion of the slug. As soon as this occurs further movement of the slug will move the latch to the dotted line position of Figure I, and immediately the spring 13 will function 65 to raise the bearing 9 and its attached parts to a position above the uppermost margin of the slug, so that further movement of the slug past the cutter head will not result in any mutilation of the type face. Both ends of 70

the slugs are low slugged in the same manner.

It is to be understood that the forms of my invention herewith shown and described, are to be taken as preferred examples of the same and that various changes relative to the shape, size, material and arrangement of parts may be resorted to without departing from the spirit of the invention, or the scope of the subjoined claims.

10 Having thus described my invention, I claim:-

1. In a low slugging device, a support, a pair of guides positioned on said support, a movable bearing positioned adjacent said

15 guides, a cutter-head carried by said bearing, an arm positioned on said support, a latch carried by said bearing and engaging said arm to hold said bearing in depressed position with relation to said guides and a spring for moving said bearing away from said

20 guides when said latch is contacted by a slug passing between said guides.

2. In a low slugging device, a support, a bearing movably mounted in said support,

25 spring means interposed between said support and said movable bearing for maintaining said bearing in elevated position, a plate secured to said support and having an arm extending therefrom, a latch mechanism pivoted to said bearing and having its nose engaging said arm, a cutter head carried by said bearing, and a horn formed on said latch and adapted to be engaged by a slug moving into engagement with said cutter-head.

3. In a low slugging device, a support having an arm mounted thereon, a movable bearing vertically movable on said support, a pair of guides positioned beneath said bearing, a rotatable cutter head carried by said bearing, spring means for normally maintaining said bearing in elevated position, a latch carried by said bearing and adapted to have the nose thereof underlie said arm for the purpose of holding said bearing in depressed

40 position against the tension of said spring, and a horn formed on said latch and adapted to be engaged by a slug moving into engagement with said cutter head whereby said nose of said latch will be moved out of engagement with said arm.

In testimony whereof I affix my signature.

CHARLES W. CURLE.
